FIG. 4.

UNITED STATES PATENT OFFICE.

SEDGWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

SIGNALING SYSTEM FOR SINGLE-TRACK RAILWAYS.

1,300,080.

Specification of Letters Patent.

Patented Apr. 8, 1919.

Application filed December 7, 1915. Serial No. 65,458.

To all whom it may concern:

Be it known that I, SEDGWICK N. WIGHT, a citizen of the United States, and a resident of the city of Rochester, in the county of Monroe and State of New York, have invented a new and useful Signaling System for Single-Track Railways, of which the following is a specification.

This invention relates to electrically operated signaling systems for governing railway traffic, and more particularly to block signaling systems for single track railways.

Signaling systems for single track railways have been devised which afford adequate protection and facility for the movement of trains, such as, for instance, the system which is disclosed in my prior application, Serial No. 753,892, filed March 13th, 1913. In this system the signals are controlled so as to protect properly trains traveling in opposite directions and trains traveling in the same direction, the character of protection in these cases being different in accordance with the principle that the space interval necessary for safety must be greater between two trains traveling toward each other than between two trains traveling in the same direction. While such a system satisfies practically all the requirements of safety and facility, there is one unusual traffic condition in which trains are not as fully protected as they might be, namely, the condition where a train having entered a stretch of single track between passing sidings, changes the direction of its movement for some reason and attempts to return to the siding from whence it came; and this invention particularly deals with this unusual traffic condition.

One of the objects of this invention is to devise a signaling system for single track railways which affords adequate protection for a train making a reverse movement of the kind above mentioned.

Other objects and advantages will appear as the description of the invention progresses, and the novel features of the invention will be particularly pointed out in the appended claims.

Generally, stated, the invention consists in the parts, and in the arrangements and combinations of parts, together with the electrical controlling circuits therefor, which are fully set forth hereinafter.

To enable a clear understanding of the nature and utility of this invention, part of a complete signaling system for single track railways is illustrated in the accompanying drawing, the circuits and controlling devices with which this invention deals more particularly being added to this system; but it is to be understood that the particular application shown illustrates only one physical embodiment of the means contemplated by this invention, and that this invention may be applied to other signaling systems of appropriate arrangement of circuits and controlling devices.

In the accompanying drawing wherein is illustrated the preferred physical embodiments of the invention and wherein like reference characters designate corresponding parts in the several views, Figure 1 is a schematic view of a portion of a stretch of single track adjacent to one passing siding, with the signals, controlling devices and controlling circuits therefor constituting a practical signaling system suitable for this portion of the trackway, this figure being a reproduction of a like figure in my prior application above mentioned, and showing in heavy lines the circuits constituting the improvement embodying this invention; Fig. 2 is a similar view showing a modified arrangement of devices and controlling circuits therefor; Fig. 3 is a similar view showing a further modified arrangement; and Fig. 4 is a similar view showing a still further modified arrangement.

Referring to Fig. 1 of the accompanying drawing, the two track rails 1 and 2 of the stretch of single track adjacent to the passing siding S are divided by insulating joints 3 into a series of track sections, A, B, C, D and E, of which there are shown three complete track sections, B, C, and D, with the end portions of the two adjacent track sections A and E. Each of these track sections has a track battery connected across the track rails 1 and 2 at one end of said section, and at the other ends of said sections track relays 10, 11, 12 and 13 are connected. The track battery 4 and the track relays of each of said track sections, together with the track rails thereof, constitute the well known normally closed track circuit, the operation of which will be clearly understood by those skilled in the art without further descrip-

tion. Traffic over this stretch of single track may be in either direction, as indicated by the arrows X and Y.

At the right hand end of the track section 5 D is located a signal 7 for governing traffic in the direction indicated by the arrow Y; and located at the right hand end of the track section B is another signal 5 for governing traffic in the same direction. At the 10 left hand end of the track section C is located a signal 6 for governing traffic in the direction indicated by the arrow X, and at the left hand end of the track section E is located another signal 8 governing traffic in 15 the same direction. The signal 7 at the entrance to the stretch of single track for governing traffic in the direction indicated by the arrow Y is of the type commonly known as an absolute signal, whereas the 20 other signals 5, 6 and 8 are of the type commonly known as permissive signals. The characteristics of these different kinds of signals are well known in the art, and it is deemed unnecessary to further discuss the 25 significance of these different signals, or describe in detail the mode of causing these signals to assume different aspects, so as to enable the engineer to differentiate between them, since it is obvious that this invention 30 is in nowise dependent upon the particular character of signals used, which may be lights as well as semaphores.

The signals illustrated are of any well known or suitable type of semaphore signal, adapted for use either in single or double track signaling systems. This type of signal primarily comprises an operating motor of appropriate construction for moving the semaphore from a biased position, which 35 may be termed the stop or danger position, and further comprises means to retain the semaphore in its operated position or positions. In the particular embodiment of the invention illustrated, the semaphore signals 40 are assumed to be three-position signals, that is, these signals have a vertical or 90 degree position, indicating full clear or proceed at unlimited speed, an inclined or 45 degree position indicating caution or proceed at 45 limited speed, and a horizontal or zero degree position indicating stop or danger. However, this invention is fundamentally in 50 nowise dependent upon three-position signals, and may be used without material 55 change or modification with two two-position signals arranged as home and distant signals, instead of three-position signals.

Associated with each of the signals 5, 6, 7 and 8 is a relay, hereinafter termed a line 60 relay, said relays for said signals being designated 14, 15, 16 and 17 respectively. Associated with each of the signals 5, 6 and 7 is a relay, hereinafter termed a stick relay, said stick relays being designated 18, 19 and 65 20; and also associated with each signal is a

suitable source of electric current, as a battery, said batteries being designated 21, 22, 23 and 24. Also associated with each of the signals 5, 6 and 7 is a pole changing circuit controller, which is arranged to be operated 70 in any suitable way by the movement of the corresponding signal, said pole changing circuit controllers being designated 25, 26 and 27. These pole changing circuit controllers 75 25, 26 and 27 are in the position shown in the drawing when the corresponding signals are in their 90 degree or proceed positions, and said circuit controllers remain in this position even after the respective signals move to their 45 degree or caution position, but shift 80 quickly to their other position (indicated by dotted lines on the drawing) when the corresponding signal moves from its caution position to its stop position, said circuit controllers remaining in their other position so 85 long as the corresponding signal remains in its stop position. Associated with each of the signals 5, 6 and 7 is another circuit controller, which is represented according to established convention, said circuit controllers being designated 28, 29 and 30, respectively. These circuit controllers are closed during the movement of the corresponding signal from its vertical proceed position to a 90 position near its caution position, the exact extent of the angular movement of the corresponding signal during which said circuit controller is closed, being dependent upon the operating characteristics of the signal and its controlling relays, the purpose of 100 these circuit controllers being more clearly set forth hereinafter.

Associated with the signal 8 is a circuit controller 31, which is closed while said signal 8 is in its 90 degree or 45 degree position 105 or any intermediate position, but which is open while said signal is in its stop position.

Although certain relays are herein designated as track relays, certain others as line relays and certain others as stick relays, 110 these designations are chosen merely for the sake of convenience; and it is to be understood that there is no essential difference in reality between the relays so designated, since each of these relays are of any of the 115 well known or ordinary types used for signaling purposes; and any distinction between these relays is due, not to differences in their construction, but rather to the different uses to which they are put. 120

Extending the full length of the track-way protected by the signaling system, is a common wire, designated K, and for convenience certain of the circuits hereinafter traced will be traced from the common wire 125 at one point back to the common wire at another point, it being obvious that this common wire acts to complete these circuits.

Associated with the signal 8 is a pole 130

changer magnet 32 having two armatures 33 and 34 arranged with contacts and connections to reverse the polarity of the connection between the battery 24 and a certain 5 circuit hereinafter traced.

In order to enable a clear understanding 10 of the nature and utility of this invention, without, however, attempting to describe in detail the circuits and operation of the single track signaling system shown, since that signaling system is fully shown and described in my prior application hereinbefore mentioned, a brief general description of the operation of this system will be given, 15 the circuits which have special significance with regards to this invention being set forth in detail.

Operation.—Disregarding for the present the particular improvement embodying this 20 invention, assume that a train enters the stretch of single track from the passing siding S traveling in the direction indicated by the arrow Y. When the train enters the track section D, the track relay 12 will be 25 deenergized, as will be clearly understood by those skilled in the art of railway signaling, and its armature 37 will drop and interrupt the circuit which normally energizes the line relay 16, said circuit being as 30 follows:

Circuit number one.

Commencing at the common wire K, conductor 35, line relay 16, conductor 36, armature 37 of the track relay 12 in its upper position, conductor 38, armature 39 of the track relay 11 in its upper position, conductor 40, armature 41 of the stick relay 19 in its lower position, conductors 42 and 43, armature 44 of the track relay 14 in its upper position, conductors 45, 46 and 47, upper conducting arm 48 of the pole changer 25, conductors 49, 50 and 51, battery 21 conductors 52 and 53, lower conducting arm 54 of the pole changer 25 and conductor 55 back to the common wire K.

When the line relay 16 is deenergized its armature 58 drops and interrupts the normally closed circuit which maintains the signal 7 in an operated position, said circuit for said signal 7 being as follows:

Circuit number two.

Commencing at the battery 23, conductors 55 and 57, armature 58 of the line relay 16 in its upper position, conductors 59 and 60, signal 7, conductors 61, 62 and 63 back to the battery 23.

The deenergization of the track relay 12 also deenergizes the line relay 15 associated with the signal 6, the normally closed circuit for said line relay 15 being as follows:

Circuit number three.

Commencing at the common wire K, conductor 64, line relay 15, conductor 65, armature 66 of the track relay 11 in its upper position, conductor 67, armature 68 of the track relay 12 in its upper position, conductors 69 and 70, armature 33 of the pole changer magnet 32, conductors 71 and 72, 70 battery 24, conductors 73 and 74, armature 34, and conductors 75 and 76 back to the common wire K.

The deenergization of the line relay 15 causes the signal 6 to assume its stop position, the circuit for this signal 6 being substantially the same as the circuit number two for the signal 7, excepting for certain differences which will be more fully disclosed hereinafter. Also, when the line 80 relay 15 is deenergized its armature 87 drops and interrupts a circuit for energizing the line relay corresponding to the line relay 15 for the next signal to the left of the signal 6 which governs traffic in the direction indicated by the arrow X, the circuit for the aforesaid other line relay being incomplete in the drawing but being easily traced as follows: commencing at the common wire K, conductor 77, lower conducting arm 78 of the pole changer 26, conductors 79 and 80, battery 22, conductors 81, 82 and 83, upper conducting arm 84 of the pole changer 26, conductors 85 and 86, armature 87 of the line relay 15, conductors 90 88 and 89, armature 90 of the stick relay 18 in its lower position, conductor 91, armature 92 of the track relay 10 in its upper position and thence in a similar way as in circuit number three through the track relay for the track section A and through said other line relay. This other line relay, in turn, in the same way, deenergizes the line relay for the next signal to the left of the other signal controlled by it which governs traffic in the direction indicated by the arrow X; and so on until the left hand end of the stretch of single track is reached, and including the absolute starting signal at that left hand end of said stretch of single track.

The signal 8 at the time when the train in question enters the track section D is in its biased danger position, since this signal is controlled by the line relay 17, and since the circuit for this line relay 17 is controlled by the armature 96 of the track relay 13 of the track section E. Only part of the controlling circuit for the line relay 17 is shown, it being understood that the control for this line relay is taken from ahead, at the right, from the next adjacent track relay, the part of the circuit for the line relay 17 which is shown being as follows: from the common wire K, conductors 76, 93 and 94, line relay 17, conductor 95, armature 96 of the track relay 13 in its upper position, conductor 97 and thence to the next track relay ahead. Also, at the time the train in question enters the track section D, the signal 6 is in 130

its 45 degree or caution position, since the signal 6 is controlled by the line relay 15, and the controlling circuit number three for the line relay 15 is controlled by the pole changer magnet 32, which pole changer magnet is controlled in part by the circuit controller 31 actuated by the signal 8, the portion of the circuit shown for the pole changer magnet 32 being as follows: commencing at 10. the common wire K, conductors 76, 93, and 98, pole changer magnet 32, conductor 99, circuit controller 31 and conductor 100. The circuit controller 31 is so constructed as to open this partial circuit when the signal 8 15 assumes its biased stop position, whereby the deenergization of the pole changer magnet 32 reverses the polarity of the circuit number three for the line relay 15 and causes its polar armature 200 to open the following 20 circuit for controlling the 90 degree or proceed position of the signal 6.

Circuit number four.

Commencing at the battery 22, conductors 25 81, 82 and 117, armature 118 of the line relay 15 in its upper position, conductors 119 and 201, polar armature 200 of the line relay 15, conductor 202, signal 6, conductors 121 and 127, armature 128 of the stick relay 18 30 and conductors 129, 125, 126 and 80 back to the battery 22.

When the train in question enters the track section C the track relay 11 is deenergized and its armature 39 drops and 35 opens another break in the circuit number one for the line relay 16, and thereby holds the signal 7 in its stop position. Also, when the track relay 11 is deenergized, its armature 66 opens another break in the circuit 40 number three for the line relay 15, thereby holding the signal 6 in its stop position.

As the train in question proceeds farther and enters the track section B it causes the deenergization of the track relay 10, and 45 the armature 37¹ of said track relay 10 drops and opens the circuit for energizing the line relay 14, said circuit being analogous to the circuit number one for the line relay 16, so that the signal 5 assumes its stop 50 position, in the same way as the signal 7 assumed its stop position when the train entered the track section D.

When the track relay 10 is deenergized, and while the signal 5 is assuming its stop 55 position the stick relay 18 is energized, this energizing circuit for the stick relay 18 being as follows:

Circuit number five.

60 Commencing at the battery 21, conductors 51 and 101, circuit controller 28 associated with the signal 5, conductor 102, armature 103 of the track relay 10 in its lower position, conductors 104 and 105, stick relay 18, 65 conductors 106, 107 and 52 back to the bat-

tery 21. The circuit controller 28 is closed during a portion of the movement of the signal 5 toward its stop position, and since the armature 103 of the track relay 10 drops much quicker than the signal 5 moves to its 75 stop position, this energizing circuit for the stick relay 18 is temporarily closed; and after the stick relay 18 has been energized its armature 111 is raised to complete a stick circuit therefor as follows:

Circuit number six.

Commencing at the battery 21, conductors 51, 50 and 108, armature 109 of the line relay 14 in its lower position, conductor 110, armature 111 of the stick relay 18 in its upper position, conductors 112 and 105, stick relay 18, conductors 106, 107 and 52 back to the battery 21. The armature 114 of the stick relay 18 being raised by the energization of 85 said stick relay closes the shunt including conductors 113 and 115 for the armature 44 and its contacts included in the circuit number one for the line relay 16, so that although the line relay 14 is deenergized and 90 would, except for the armature 114 of the stick relay 18, interrupt this circuit number one, this circuit number one is nevertheless complete and the line relay 16 reenergized 95 to cause the signal 7 to assume its 45 degree or caution position, the 45 degree position of 95 said signal 7 resulting from the movement of the pole changer 25 by the signal 5.

From the above brief description of the 100 operation of the system of signaling for single track railways which is disclosed in my prior application hereinbefore mentioned and to which the improvement embodying this invention is shown applied, it can be seen that when a train has moved in the direction indicated by the arrow Y entirely into the track section B, the signal 7 will be in its 45 degree or caution position. It can also be seen that the signal 6, even though a 105 following train occupies the track section E, is in its 45 degree or caution position. Consequently, if the first train in the track section B wishes to make a reverse movement back to the siding S, it is only protected by a caution aspect at the signal 7; and if the 110 first train accepts the signal 6 in its caution position and the following train accepts the signal 7 in its caution position, two trains will be entering the same block. To obviate this dangerous condition it 115 is contemplated according to this invention to make the control of the signal 6 dependent upon the track relay of the track section E or of other track sections ahead of it at the right in Fig. 1, whenever a train passes the signal 6 traveling in the direction indicated by the arrow Y. The signal 8 is controlled in the same way as it would be if the train in the track section B did not attempt to make a reverse move, since the or- 120 125 130

derly operation of the system entitles a following train to enter the track section D and proceed up to the signal 5.

Fig. 1 shows one arrangement of circuits and controlling devices for accomplishing this result and in this arrangement the control of the signal 6 is so formulated that said signal 6 cannot move from its stop position unless it can move to its full clear position, providing a train has passed the signal 6 traveling in the direction indicated by the arrow Y and occupies the track sections A or B. The controlling circuit for the signal 6 is drawn in heavy lines and is as follows:

15 *Circuit number seven.*

Commencing at the battery 22, conductors 81, 82 and 117, armature 118 of the line relay 15 in its upper position, conductors 119 and 120, signal 6, conductor 121, and thence along either one of two paths, one path being along conductor 122, polar armature 123 of the line relay 15, conductors 124, 125, 126 and 80 back to the battery 22, and the other 25 path being along conductor 127, armature 128 of the stick relay 18 in its lower position, conductors 129, 125, 126, and 80 back to the battery 22.

This circuit just traced is for the control 30 of the 45 degree or caution position of the signal 6, but, as can be seen from circuit number four, hereinbefore traced, the 90 degree or proceed position is also controlled through the polar armature 123 of the line 35 relay 15 in parallel with the armature 128 of the stick relay 18.

Hence, when the track section E is occupied and the signal 8 is in its stop position, and, for the reason hereinbefore described, 40 the pole changer magnet 32 is deenergized, the direction of flow of current in the circuit number three for the line relay 15 is such that the polar armature 123 will be in its open position, and since the stick relay 18 is energized and its armature 128 is in its upper position, the supply of current to the motor for operating the signal 6 is interrupted. Consequently, when a train travels 45 in the direction indicated by the arrow Y, as in the case first assumed, the armature 128 of the stick relay 18 breaks the shunt around the polar armature 123 and makes the signal 6 entirely subservient to the control of the pole changer magnet 32.

55 It is essential, however, that the signal 6 should be able to assume its caution position, although a train occupies the track section E, when the train has passed said signal 6 traveling in the direction indicated by the arrow X, in order that the signal 6 may perform its proper function as a distance indication for the signal 8. This result is accomplished in the arrangement shown in Fig. 1 by providing the shunt for the polar armature 123 of the line relay 15, which shunt is

controlled by the armature 128 of the stick relay 18. Consequently, when a train traveling in the direction indicated by the arrow X enters the track section B, the signal 5 is already in its stop position by reason of the 70 deenergization of the line relay 14 by the presence of the train in the track section A; and circuit number five for energizing the stick relay 18 is broken at the circuit controller 28 of the signal 5, and the armature 75 128 of said stick relay remains in its lower position. This armature 128 of the stick relay 18 in its lower position shunts the polar armature 123 of the line relay 15 so that the signal 6 may assume its 45 degree or caution 80 position although the track section E is occupied.

Fig. 2 shows another way of controlling the signal 6 so that the undesirable condition above mentioned cannot occur. In this arrangement, the control of the signal 6, whenever a train passes said signal 6 traveling in the direction indicated by the arrow Y, is placed in the track relay 13 of the track section E, or, if desired, in other track sections at the right of the track section E. Both the stop and caution positions of the signal 6 are controlled by the line relay 15, and the controlling circuit for the line relay 15 is as follows: commencing at the common 95 wire K, conductor 64, line relay 15, conductor 65, armature 66 of the track relay 11 in its upper position, conductor 67, armature 68 of the track relay 12 in its upper position, conductors 69 and 70, armature 33 of 100 the pole changer magnet 32, conductors 71 and 72, battery 24, conductors 73 and 74, armature 34 of the pole changer magnet 32, conductors 75 and 76, from whence there are two paths to the common wire K, one of 105 these paths being along conductor 133, armature 128 of the stick relay 18 in its lower position and conductors 135 and 136, the other path being along conductor 130, armature 131 of the track relay 13 in its upper 110 position and conductor 132 to the common wire K. From the above traced circuit it can be seen that when the stick relay 18 is energized, as it will be when a train passes the signal 5 traveling in the direction indicated by the arrow Y, because of the operation of the parts and circuits hereinbefore described, the line relay 15 is controlled by the armature 131 of the track relay 13, so that, if a train occupies the track section E, 115 the line relay 15 will be deenergized and the signal 6 will be in its stop position.

Fig. 3 shows a still further slightly different arrangement of circuits and controlling devices for accomplishing the same result; and in this arrangement, an additional relay 137 is used, said relay having an armature 138 included in series in the controlling circuit for the line relay 15, said armature being shunted by the armature 128 130

of the stick relay 18. The relay 137 is controlled by the armature 131 of the track relay 13, the controlling circuit for said relay 137 being as follows: commencing at the common wire K, conductors 64 and 147, relay 137, conductor 148, armature 131, of the track relay 13, conductors 150, 69¹ and 70, armature 33 of the pole changer magnet 32, conductors 71 and 72, battery 24, conductors 73 and 74, armature 34 of the pole changer magnet 32 and conductors 75 and 76 to the common wire K. From this last traced circuit it can be seen that when a train occupies the track section E the auxiliary relay 137 will be deenergized. The controlling circuit for the line relay 15 in the arrangement shown in Fig. 3 is as follows: commencing at the common wire K, conductors 64 and 64¹, line relay 15, conductor 65, armature 66 of the track relay 11 in its upper position, conductors 67 and 140, armature 138 of the auxiliary relay 137, conductors 141 and 142, armature 68 of the track relay 12 in its upper position, conductors 69, 69¹ and 70, armature 33 of the pole changer magnet 32, conductors 71 and 72, battery 24, conductors 73 and 74, armature 34 of the pole changer magnet 32 and conductors 75 and 76 to the common wire K. The shunt for the armature 138 of the auxiliary relay 137 is as follows: commencing at one side of the armature 138, conductors 140 and 144, armature 128 of the stick relay 18 in its lower position and conductors 146 and 141 back to the other side of the armature 138. From the foregoing circuits it can be seen that when a train passes the signal 6 traveling in the direction indicated by the arrow Y and the stick relay 18 is energized, the line relay 15 is placed under the control of the auxiliary relay 137, which in turn is controlled by the track relay 13 of the track section E, so that if a train occupies said track section E the auxiliary relay 137 will be deenergized, the line relay 15 will also be deenergized, and the signal 6 will assume its stop position.

Fig. 4 shows a still further slightly different arrangement of circuits and controlling devices for accomplishing the same result; and in this arrangement, an additional neutral relay 156 for controlling the 90 degree or proceed position of the signal 6 is provided, said relay having an armature 158 included in the controlling circuit for the proceed position of the signal 6. The circuit for controlling the auxiliary relay 156 is as follows: commencing at the common wire K, conductors 64 and 155, relay 156, conductor 157, circuit controller 31 of the signal 8, conductor 100 and thence to the line relay associated with the next signal to the right of the signal 8.

The line relay 15 has the same neutral ar-

mature 118 as before and the same polar armature 200, but the polarity of the circuit for said line relay 15 is controlled, in the arrangement shown in Fig. 4, by the track relay 13 of the track section E, the controlling circuit for said line relay 15 being as follows: commencing at the common wire K, conductors 64 and 64¹, line relay 15, conductor 65, armature 66 of the track relay 11 in its upper position, conductor 67, armature 68 of the track relay 12 in its upper position, conductors 69 and 160, armature 161 of the track relay 13, conductors 162 and 163, battery 24, conductors 164 and 165, armature 166 of the track relay 13, and conductor 167 to the common wire K.

All supply of current to the operating motor of the signal 6, both for moving the signal to its proceed position and for moving said signal to its caution position, is controlled by the neutral armature 118 of the line relay 15 in series with the polar armature 200 of said line relay, the polar armature, however, being shunted by conductor 172, armature 128 of the stick relay 18 in its lower position and conductors 171, 170 and 202. The circuit for operating the signal 6 to its 45 degree or caution position is as follows: commencing at the battery 22, conductors 81, 82 and 117, armature 118 of the line relay 15 in its upper position, conductor 119, polar armature 200, conductors 202 and 159, signal 6, and conductors 121, 126 and 80 back to the battery 22.

The circuit for operating the signal 6 to its proceed or 90 degree position follows the same path as the last circuit traced through the polar armature 200 and thence by conductors 202 and 170, armature 158 of the auxiliary relay 156, conductor 169, signal 6 and conductors 121, 126 and 80 back to the battery 22.

From these circuits it can be seen that the 90 degree or proceed position of the signal 6 is controlled in part by the auxiliary relay 156, which in turn is controlled by the circuit controller 31 of the signal 8; and in this way the signal 6 is controlled to perform its function as a distant indication for the signal 8. The polar armature 200 of the line relay 15, together with the armature 161 and 166 of the track relay 13, arranged as a pole changing device, serve to repeat the condition of the track section E at the signal 6; and this information is used to control the signal 6 in such a way that the train making a reverse move of the character described will be fully protected. To explain further, assume that a train passes from the siding S over the stretch of single track in the direction indicated by the arrow Y and passing entirely into the track section B, and further assume that this train wishes to make a reverse move, and further assume

that another train occupies the track section E. The presence of a train on the track section E deenergizes the track relay 13 and reverses the polarity of the line relay 15, thereby opening its polar armature 200; and since the stick relay 18 was energized by the movement of the first train, the shunt around the polar armature 200 is broken, so that all supply of current to the operating motor 10 of the signal 6 is cut off, and said signal 6 will assume its stop position. Assume, however, that a train passes along the stretch of single track traveling in the direction indicated by the arrow X and enters the track section E. Under these conditions the polarity of the flow of current of the line relay 15 would be reversed and the polar armature 200 moved to its open position, but the movement of the train in the direction specified 20 past the signal 6 would not affect the stick relay 18, for the reason hereinbefore explained, so that current to the signal could be supplied through the shunt around the polar armature 200, thereby placing the proceed position of the signal under the control of the auxiliary relay 156 and the caution position of said signal under the control of the line relay 15.

The arrangement of circuits shown in 30 Figs. 2, 3 and 4, in the same way as in the arrangement of circuits shown in Fig. 1, is such that the stick relay 18 must be energized to place the signal 6 under the control of the track relay 13 of the track section E; 35 and consequently the signal 6 may assume its 45 degree or caution position for a train traveling in the direction indicated by the arrow X, although the track section E is occupied by another train.

40 Various changes may be made in the particular arrangements of circuits and controlling devices shown and described without departing from the invention or the physical embodiment thereof illustrated; and also this 45 invention may be applied to other signaling systems. Also, although the particular embodiment of the invention shown is designed to be operated by direct current, simple modifications apparent to those skilled in the 50 art of railway signaling, may be made where alternating current may be used as an operating medium. The number of track sections into which the stretch of single track may be divided may be different according 55 to different conditions without affecting the application of this invention; and other signals for protecting the sidings, preliminary sections, and other expedients known in the art of railway signaling may be combined 60 with this invention.

Although I have particularly described the construction of one physical embodiment of my invention, and explained the operation and principle thereof; nevertheless, I

desire to have it understood that the form 65 selected is merely illustrative, but does not exhaust the possible physical embodiments of the idea of means underlying my invention.

What I claim as new and desire to secure 70 by Letters Patent of the United States, is:

1. In a signalling system for railways, in combination: a stretch of trackway divided into electrically isolated track circuited sections, each having a track relay, a signal 75 for governing traffic in one direction over said stretch of trackway; a circuit for controlling said signal; means governed by the track relay of a section succeeding the portion of said trackway protected by said sig- 80 nal for controlling said signal circuit; and means for nullifying the controlling effect produced on said signal circuit by said means, said last-mentioned means being set into operation by the movement of a train 85 in the direction opposite to the direction of traffic governed thereby.

2. In a signaling system for railways, in combination: a stretch of trackway divided into electrically isolated track circuited sections, each having a track relay; a signal 90 for governing traffic in one direction over said stretch of trackway; a second signal for governing traffic in the opposite direction; a circuit controller operated by said second signal and closed during a portion of the movement thereof from its normal position; a relay; an energizing circuit for said relay controlled jointly by said circuit controller and the track relay of the section protected by said second signal; a controlling circuit for said first signal; means governed by the track relay of a section succeeding the portion of said trackway protected by said first signal for opening a break in said sig- 100 nal controlling circuit; a shunt for said break; and means controlled by said relay and operated when it is energized for opening said shunt.

3. In a signalling system for railways, in 110 combination: a stretch of trackway divided into electrically isolated track circuited sections, each having a track relay; a signal for governing traffic in one direction over said stretch; a second signal for governing traffic in the same direction over said stretch, each of said signals having a proceed, a caution and a stop aspect; a polarized relay for controlling said first signal; a controlling circuit for said relay; means controlled by said second signal for changing the polarity of said controlling circuit; means controlled by the track relay of a section in advance of the second signal for opening and closing a 115 break in said controlling circuit according to whether said track section is respectively occupied or unoccupied by another train; a normally closed shunt for said break; and 120 125

- means set into operation by the movement of a train over said stretch of trackway in the direction opposite to the direction of traffic governed by said signals for opening said shunt.
4. In a signaling system for railways, in combination: a stretch of trackway divided into electrically isolated track circuited sections, each having a track relay; a signal for governing the traffic over said stretch in one direction; a circuit for controlling said signal; means governed by the track relay of a section succeeding the portion of said trackway protected by said signal for opening and closing a break in the controlling circuit for that signal; means associated with said means for nullifying the effect produced thereby; and means set into operation by the movement of a train in the direction opposite to the direction of traffic governed thereby for rendering the corresponding last-mentioned means ineffective.
5. In a signaling system for railways, in combination: a stretch of trackway divided into electrically isolated track circuited sections, each having a track relay; a first and a second signal for governing traffic over said stretch of trackway in one direction; a circuit for controlling said first signal; a circuit controller included in said circuit; means governed by the track relay of a section protected by said second signal for controlling said circuit controller; a normally closed shunt for said circuit controller; a relay for opening said shunt when energized; a third signal for governing traffic in the opposite direction; a second circuit controller governed by said third signal and closed for a portion of the movement thereof from its normal position; and an energizing circuit for said last-mentioned means controlled jointly by said second circuit controller and by the track relay of the section protected by said third signal.
6. In a signaling system for railways, in combination: a stretch of trackway divided into electrically isolated track circuited sections, each having a track relay; a signal for governing traffic in one direction over said stretch; a circuit for controlling said signal; a circuit controller included in said circuit; a normally closed shunt for said circuit controller; and means operated by the movement of a train past said signal in the direction opposite to the direction of traffic governed thereby for opening said shunt.
7. In a signaling system for railways; in combination: a stretch of trackway divided into electrically isolated track circuited sections, each having a track relay; a first and a second signal for governing traffic in opposite directions; a controlling circuit for said first signal having two branches in parallel; means controlled by the track relay of a track section at a distance in advance

of the first signal for opening one of said branches when a train occupies said advance section; a circuit controller included in the other branch of said circuit; a second circuit controller operated by said second signal and closed during a portion of the movement thereof from its normal position; a relay for operating said first circuit controller and adapted to open said first circuit controller when energized; and an energizing circuit for said relay controlled jointly by said second circuit controller and the track relay of the section protected by said second signal.

8. In a signaling system for single track railroads, the combination with a signal for governing traffic over a portion of the track, of controlling circuits and apparatus associated with said signal for causing it to indicate stop when said portion of the track is occupied, means capable of exerting a controlling influence suitable for causing said signal to also indicate stop and operated when another portion of the track in advance of said first mentioned portion is occupied, and means set into operation by a train moving in the direction opposite to the direction of traffic governed by said signal for permitting said last mentioned means to exert its controlling influence on said signal effectively.

9. In a signaling system for single track railroads, the combination with a signal for governing traffic over a portion of the track and having its stop aspect dependent on the presence or absence of a train on that portion, of means capable of exerting a controlling influence suitable for causing said signal to indicate stop and operated when another portion of the track in advance of said first mentioned portion is occupied, and means normally preventing the control of the signal by said means but adapted to be changed from its normal condition by a train moving in the direction opposite to the direction of traffic governed by the signal.

10. In a signaling system for single track railroads, the combination with a signal for governing traffic over a portion of the track and normally having its stop aspect dependent solely on the presence or absence of a train on that portion, of means rendered effective by a train moving in the direction opposite to the direction of traffic governed by said signal for causing the stop aspect thereof to be also dependent upon the presence or absence of a train on another portion of the track in advance of the first mentioned portion.

11. In a signaling system for single track railroads, the combination with a stretch of track comprising two successive portions of track, of a signal located at one end of said stretch, means for causing said signal to indicate stop when the adjacent portion of

said stretch is occupied, means responsive to the presence of a train on the other portion of the track remote from the signal, and means rendered effective by a train traveling in the direction opposite to the direction of traffic governed by the signal for placing said signal under the control of said last mentioned means.

12. In a signaling system for a single track railroad having a passing siding, the combination with a signal located at a distance from one end of the siding and governing traffic toward the siding, of means for causing the signal to indicate stop when a train occupies the portion of track between the signal and the siding, and means rendered active by a train moving in the direction away from the siding toward the signal for causing the stop aspect of said signal to be dependent also on the presence or absence of a train on a portion of the track between the ends of the siding.

13. In a signaling system for a single track railroad having a passing siding, the combination with a signal located at a distance from one end of the siding and governing traffic toward the siding, of means responsive to the presence of a train on the track between the signal and the siding for normally governing the stop aspect of said signal, means tending to cause said signal to indicate stop when a train occupies a portion of the track between the ends of the siding, and means normally preventing the effective action of said last mentioned means but operated to permit such action when a train moves in the direction away from the siding toward the signal.

14. In a signaling system for a single track railroad having a passing siding, the combination with a signal located at a distance from one end of the siding and governing traffic toward the siding, of controlling circuits and apparatus for causing the limits of control for the stop aspect of said signal to extend up to the adjacent end of the siding when a train moves in the direction of traffic governed by said signal and to extend up to a farther point between the ends of the siding when a train moves in the opposite direction.

15. In a signaling system for a single track railroad provided with track circuit sections and a passing siding, the combination with a signal located at a distance from one end of the siding and governing traffic toward the siding, of a circuit for controlling the stop aspect of said signal, said circuit being controlled by the track circuit sections between the signal and the adjacent end of the siding and including two branches in multiple, means governed by a track circuit section adjacent to the siding and between the ends thereof for opening one branch of said circuit when that section

is occupied, and means rendered effective by a train moving the direction away from the siding toward said signal for opening the other branch of said circuit.

16. In a signaling system for a single track railroad provided with track circuit sections and a passing siding, the combination with a signal located at a distance from one end of the siding and governing traffic toward the siding, a signal circuit for controlling the stop aspect of said signal, and circuit controlling devices adapted to effectively control said circuit when operated simultaneously, one of said devices being operated when a train occupies a track section adjacent to the siding and between the ends thereof, and the other device being operated when the train travels away from the siding toward said signal.

17. In a signaling system for a single track railroad provided with track circuit sections and a passing siding, the combination with a signal located at a distance from one end of the siding and governing traffic toward the siding, of a signal circuit for controlling the stop aspect of said signal, a circuit controller included in said circuit and opened when a train occupies a track section adjacent to the siding and between the ends thereof, a normally closed shunt for said circuit controller, and means for opening said shunt when a train travels in the direction away from said siding toward said signal.

18. In a signaling system for a stretch of single track adjacent to a passing siding, the combination with two signals located at a distance from one end of the siding and governing traffic in opposite directions, a circuit controlling device associated with each signal and adapted to be changed from its normal condition when a train travels in the direction of traffic governed by that signal, a circuit for controlling the stop aspect of the signal governing traffic toward the siding, a circuit controller opened when a portion of the track between the ends of the siding is occupied, and means for rendering said circuit controller effective to control said circuit when the circuit controlling device associated with the other signal governing traffic away from the siding is changed from its normal condition.

19. In a signaling system for a stretch of single track adjacent to a passing siding, the combination with a signal located at a distance from one end of the siding and governing traffic toward the siding, a circuit controlling device adapted to be changed from its normal condition when a train travels in the direction away from the siding and to be maintained in its changed condition until such train has advanced a predetermined distance from the siding, and means rendered effective when said circuit

controlling device is changed from its normal condition for causing the stop aspect of said signal to depend upon the presence or absence of a train on a portion of the track between the ends of the siding.

20. In a signaling system for railroads, the combination with a stretch of single track divided into track circuit sections and located adjacent to a passing siding, of a signal located at a distance from one end of the siding and governing traffic toward the siding, a polarized line relay for controlling said signal, a line circuit including said line relay and controlled by the track relays of the track sections between the signal and the adjacent end of the siding, an electrically operable pole changing device controlling the polarity of the line circuit and governed by the track relays of a predetermined portion of the track in advance of the signal and beyond the adjacent end of the siding, a circuit controller included in said line circuit and open when a train occupies a track section adjacent to the siding 25 and between the ends thereof, a normally closed shunt for said circuit controller, and means operated when a train travels in the direction away from the siding for opening said shunt and for maintaining it opened 30 until such train has advanced a predetermined distance from the siding.

21. In a signaling system for railroads, the combination with a stretch of single track provided with track circuit sections and a passing siding, of a signal located at a distance from one end of the siding and governing traffic toward the siding, a circuit for controlling the stop aspect of said signal and governed by the track relays of the track sections between the signal and the adjacent end of the siding, a circuit controller included in said circuit and opened when a train occupies a track section adjacent to the siding and between the ends thereof, a normally closed shunt for said circuit controller, and means operated when a train travels in the direction away from the siding for opening said shunt and for maintaining it opened until such train has advanced a predetermined distance from the siding.

22. In a signaling system for railroads, the combination with a stretch of single track divided into track circuit sections and located adjacent to a passing siding, of a signal located at a distance from one end of the siding and governing traffic toward the siding, a polarized line relay for controlling said signal, a line circuit including said line relay and controlled by the track relays of the track sections between the signal and the adjacent end of the siding, a pole changing device controlling the polarity of said line circuit and responsive to the presence 60 of a train on a particular track section lo-

cated adjacent to the siding and between the ends thereof, means including a circuit controller governed by said particular track section for controlling the continuity of said line circuit, a normally closed shunt 70 for said circuit controller, and means set into operation when a train travels in the direction away from the siding for opening said shunt and for maintaining it opened until such train has advanced a predetermined distance from the siding.

23. In a signaling system for railroads, the combination with a stretch of track between passing sidings and divided into track circuit sections, of signals located at intervals along the stretch for governing traffic in both directions, a signal circuit for each signal, controlling circuits and apparatus for governing said signal circuits and adapted to cause the opposing signals to indicate 85 stop when a train enters said stretch and to remain at stop until such train has successively passed these signals, and means for controlling the signal at a distance from the adjacent end of each corresponding siding and governing traffic toward that siding, said means being adapted to cause the stop control of said signal to extend to the siding when a train travels toward said siding and to extend to a point between the ends of that 90 siding when a train travels in the opposite direction.

24. In a signaling system for railroads, the combination with a stretch of single track divided into track circuit sections and located adjacent to a passing siding, of a signal located at a distance from one end of the siding and governing traffic toward the siding, a polarized line relay for controlling said signal, a line circuit including said 100 line relay and controlled by the track relays of the track sections between the signal and the adjacent end of the siding, means responsive to the presence of a train on a portion of the track in advance of the signal and 105 beyond the adjacent end of the siding for controlling the polarity of said line circuit, and means for causing the continuity of said line circuit to be dependent upon the presence or absence of a train on a predetermined portion of track located adjacent to the siding and between the ends thereof whenever a train travels in the direction 110 away from the siding toward said signal.

25. In a signaling system for railways, in combination: a stretch of trackway divided into electrically isolated track circuit sections, each having a track relay; a first signal and a second signal located at different points for governing traffic in 120 opposite directions over said stretch; a controlling circuit for said second signal; a circuit controller included in said circuit; a relay controlled by the track relay of a section in advance of the section protected 125 130

5 by said second signal for opening said circuit controller when said advance section is occupied by a train; a normally closed shunt for said circuit controller; and means responsive to the direction of movement of trains over said stretch for opening said shunt when a train moves in the direction of traffic governed by said first signal.

10 26. In a signaling system for railways, in combination: a stretch of trackway adjacent to a passing siding and divided into electrically isolated track circuited sections, each having a track relay, a first signal at one end of the siding and governing traffic away from the siding; a second signal at a distance from the end of the siding and governing traffic toward the siding; a controlling circuit for said second signal; a circuit controller included in said circuit; a 15 relay controlled by the track relay of a section in advance of the section protected by said second signal for opening said circuit controller when said advance section is occupied by a train; a stick relay; an energizing 20 circuit for said stick relay controlled by the track relays of at least two of said sections; a circuit controlling device operated by said stick relay and closed when it is energized; a maintaining circuit for said stick relay 25 controlled by said circuit controlling device and by the track relays of one or more of said sections; a normally closed shunt for said first mentioned circuit controller; and means operated by said stick relay for opening 30 said shunt when said stick relay is energized.

35 27. In a signaling system for railroads, the combination with a stretch of single track and a passing siding, of a signal governing

40 traffic away from the siding, a second signal located beyond the first signal and governing traffic toward the siding, a signal circuit for controlling the stop aspect of said second signal and controlled by the track circuit sections of the track between said signal and 45 the adjacent end of the siding, a circuit controller included in said circuit, a relay for operating said circuit controller, a controlling circuit for said relay governed by a track circuit section adjacent to the siding and 50 between the ends thereof, a normally closed shunt for said circuit controller, and means for opening said shunt when a train travels in the direction away from the siding and for maintaining it open until such train has 55 advanced a predetermined distance from the siding and beyond the second signal.

28. In a signaling system for railroads, the combination with a stretch of single track having a passing siding and divided into 60 track sections each provided with a track circuit, of a signal located at a distance from one end of the siding and governing traffic toward the siding, a signal circuit for said signal controlled by the track circuits of the 65 sections between the signal and the adjacent end of the siding, a relay for controlling the continuity of said signal circuit, a controlling circuit for said relay governed by a track circuit located adjacent to and between the ends of the siding, and means for maintaining the continuity of said signal circuit independently of said relay, said means being rendered ineffective by a train traveling away from the siding and being 70 maintained ineffective until such train has advanced beyond said signal. 75

SEDGWICK N. WIGHT.

Copies of this patent may be obtained for five cents each, by addressing the "Commissioner of Patents,
Washington, D. C."

It is hereby certified that in Letters Patent No. 1,300,080, granted April 8, 1919, upon the application of Sedgwick N. Wight, of Rochester, New York, for an improvement in "Signaling Systems for Single-Track Railways," an error appears in the printed specification requiring correction as follows: Page 7, lines 90 and 112, claims 2 and 3, for the word "circulated" read *circuited*; and that the said Letters Patent should be read with this correction therein that the same may conform to the record of the case in the Patent Office.

Signed and sealed this 13th day of May, A. D., 1919.

[SEAL.]

R. F. WHITEHEAD,

Acting Commissioner of Patents.

Cl. 246 -33.
